PERMANENT WAVE APPARATUS

Frank G. Hall, Chicago, Ill., assignor to Halgar,
Inc., Chicago, Ill., a corporation of Illinois

Application May 5, 1938, Serial No. 206,222

7 Claims. (Cl. 132—36)

This invention relates to improvements in apparatus for permanently waving hair, and more particularly to hair-waving apparatus of simple and economical form capable of use by a woman for home treatment of her own hair or the hair of others, without requiring complicated accessories such as electrical attachments or the practice of extraordinary skill in manipulating the apparatus.

10 The present invention is based upon a form of apparatus broadly disclosed in the co-pending application for Letters Patent of Carlota de la Garza, Serial No. 148,703, filed June 17, 1937, and is especially directed to improvements in the 15 construction of the wrapper or curler, and metal heat reflecting and protective shield used therewith.

One of the most serious difficulties heretofore encountered in the use of hair waving apparatus 20 is the danger from burns or scalds caused by discharge of steam toward the scalp during the heating process. Substantial protective devices, such as thick felt pads, are usually placed next to the scalp, and other forms of shields have also 25 been inserted between the curl and scalp during the heat treatment. Nevertheless, scalp burns are still of frequent occurrence, even under skilled hands, due to accidental twisting or displacement of the wrapped curl relative to its protective pad so as to permit a jet of steam generated 30 in the wrapper to be discharged over the side of said pad toward the scalp.

In carrying out the present invention, I provide an improved form of curl wrapper including 35 a metal reinforcing member serving to assist in curling the hair strand into a straight, relatively compact roll which is more readily maintained in proper position during the subsequent heating stage, and also provide a new form of heat reflecting and protective shield which co-operates 40 with the wrapped roll and the heating pad so as to increase the heating effect of the latter and also protect the scalp from accidental steam burns.

45 The invention may best be understood by reference to the accompanying drawing, in which

Fig. 1 is a view illustrating the method of application of my improved form of hair-waving apparatus.

50 Fig. 2 is an enlarged perspective view showing parts of the apparatus in an initial stage of application to a strand of hair ready for wrapping or curling the latter into a roll.

55 Fig. 3 is a view similar to Fig. 2, but showing

the strand wrapped into a roll ready for application of the exothermic pad.

Fig. 4 is a detail view of the exothermic pad.

Fig. 5 is a view similar to Figs. 2 and 3, but showing the exothermic pad applied about the 5 roll, in final condition for heat treatment.

Fig. 6 is an enlarged transverse section of the apparatus arranged as shown in Fig. 5.

Fig. 7 is a view similar to Fig. 5, but showing the roll and protective shield in a twisted position relative to the felt pad, but without danger of scalp burn to the wearer.

Fig. 8 is a detail view of a metal protective shield forming one of the novel features of my improved apparatus.

Fig. 9 is a detail view of a felt pad forming a part of the apparatus.

Fig. 10 is a detail view of a fibre shield optionally usable in connection with my improved form of apparatus.

Referring now to details of the embodiment of the invention shown in the drawing, the principal parts of the apparatus comprise a felt pad 10, a metal shield 11, a wrapper 12 and an exothermic pad 13. The felt pad 10 is of the usual form having a longitudinal slit 14 therein through which a strand or tress 15 of hair to be treated is passed, and the pad is then brought against the scalp, as indicated in Figs. 2 and 6. In preparation for treatment, the strand of hair is moistened as usual with a permanent wave or hair-treating solution.

The protective shield 11 shown in detail in Fig. 8 is preferably made of sheet metal such as aluminum, and is provided with upturned flanges 16, 16 along opposite sides thereof so as to form in effect a trough for receiving the assembled hair roll and exothermic pad when the latter are finally secured thereon, as will hereinafter more fully appear. Said shield is also provided with a centrally disposed elongated slot 11^a adapted to receive the hair strand in spread form prior to curling, as shown in Fig. 2. A connecting slot 11^b permits the hair strand to be passed into the center slot 11^a from one edge of the shield.

The wrapper 12 includes an elongated strip of cloth such as flannel, folded upon itself to form two lapping sheets 17, 18, one of which is preferably slightly longer than the other. Along the folded end of the wrapper is disposed a pair of insulated wires 19 and 20 having bendable end portions 19^a, 19^b and 20^a, 20^b, respectively, projecting at opposite sides of the wrapper, as clearly shown in Fig. 2. The structural features of the wrapper above described are similar to those 55

broadly disclosed in the de la Garza application Serial No. 148,703 above referred to. In the improved form disclosed herein, a metal reinforcement, preferably consisting of a rigid U-shaped clip 21, is clamped over said sheets and wires 19 and 20 along the folded edge of sheets 17 and 18, so as to hold the wires firmly in place along the edge of said wrapper, as shown.

The exothermic heat pad 13 may consist of the usual flat foil envelope 18 containing a suitable exothermic powder, and having one wall thereof perforated at intervals, as shown in Fig. 4. When ready for application, water is applied to a sheet of cloth or absorbent paper 24, and the dampened sheet is then placed over the perforated side of the exothermic pad. The water, passing through the perforations, chemically reacts as usual with the exothermic powder to produce heat.

The auxiliary shield 25 shown in Fig. 10 is an optional part of the apparatus, and consists of a flat sheet of fibre or rubber formed with a center slot 26 and communicating slot 27, and adapted to be applied beneath the felt pad 18 next to the scalp, if desired. Heretofore, shields of this general form have often been applied over the felt pad 18, but due to the added advantage of my improved form of metal shield 11 to be hereinafter more fully described, such fibre or rubber shields can be dispensed with.

The use and operation of the apparatus above described may now be explained as follows:

Each strand of hair 15 which is to be waved is separated from the surrounding hair and passed through the slit 14 of a felt pad 18. The pad 18 is then pushed tightly toward the scalp. If an auxiliary shield 25 is to be used, it is first inserted between the felt pad and the scalp. The strand is then moistened with a suitable permanent wave solution.

The metal shield 11 is then applied to the hair strand, with said strand spread out along the central slot 11a and with said shield pushed against the outer face of the felt pad 18, as shown in Fig. 2.

The wrapper 12 is initially applied to the end of the strand as shown in the same figure. For convenience, the shorter sheet 18 is held uppermost, and the wrapper is then rolled over and inwardly toward the head. The sheets 17 and 18, together with the strand, are thus rolled on the metal strip 21, which provides a rigid base for this purpose and assists in forming a smooth, even and compact roll of hair, which is brought tightly against the shield 11 and between the upstanding flanges 16 thereof, as shown in Fig. 3. The roll is now ready for heat treatment by application of an exothermic pad.

The operator may, of course, elect whether to proceed at once with the heating process, or wait until the remaining strands of hair are similarly rolled on other wrappers in the same manner, before applying any heat pads. But in either case, it is necessary to hold each roll securely in place while the heat pad is being applied. For this purpose, one pair of the two wire ends projecting from opposite ends of the wrapper are employed, as for instance as shown in Fig. 3, wherein the wire ends 19a and 19b are bent in direction along the adjacent sides of the roll, thus holding the hair and wrapper securely against unwrapping.

After wetting and applying the absorbent sheet 24 to the perforated side of the exothermic pad, 75 said pad and sheet are applied over the roll with

the wet sheet toward the hair, as shown in Figs. 5 and 6. The exothermic pad is of such shape and size to fit around the exposed sides of the roll and with its side margins in engagement with the outer face of the metal shield 11 between the opposite upstanding flanges 16 thereof, as clearly seen in these figures. The pad is finally secured snugly in this position by means of the second pair of wires 20a and 20b projecting from the ends of the wrapper. These wire ends are bent along the outside surfaces of the exothermic pad closely adjacent the lower margins of the latter, but in each instance preferably extend toward the side opposite to the companion wires 19a and 19b, respectively, as clearly indicated in Fig. 5. The heating pad is thus securely held against the metal shield 11 so that the latter forms in effect a closed metallic wall for the heating pad, and due to the heat-reflecting surface provided by the shield, the heat from said pad is conserved and directed more effectively to the under surface of the roll.

It will be observed further, that the upturned flanges 16 of the metal shield serve to confine and hold the side margins of the heating pad in alignment therebetween, so that the shield moves bodily with the roll. This feature has especial advantages over prior forms of shields similar to the form shown in Fig. 10, on which the roll often tended to become twisted laterally so that the ends of the roll would project beyond the sides of such shield and the felt pad thereunder, and thus permit jets of steam to escape from the ends of the roll toward the scalp during the heating operation, so as to produce serious scalds and burns. With my improved form of apparatus, the shield moves bodily with the roll when it becomes twisted laterally, as indicated in Fig. 7, thus protecting the scalp from burns or scalds at all times.

When the heating pads cool off, the outer two wires of each are then bent outwardly or straightened to permit removal of said pad. The inner pairs of wires are then bent outwardly and the curled strands of hair and their wrappers are unwound. The shield and felt pads are also removed, and the hair is ready for usual treatment, such as rinsing in water, drying and final arrangement of the curls or waves on the head.

It will be understood that the wrappers, pads and shields can be used repeatedly, while new exothermic pads can be supplied for each treatment. The apparatus is therefore extremely economical and simple in construction and operation, and has been rendered safe in unskilled hands as improved by the present invention.

Although I have shown and described certain embodiments of my invention, it will be understood that I do not wish to be limited to the exact construction shown and described, but that various changes and modifications may be made without departing from the spirit and scope of my invention as defined in the appended claims.

I claim as my invention:

1. In combination in a hair waving apparatus, 65 a protective shield having rigid upturned flanges along opposite sides and a centrally disposed slot for passing a strand of hair therethrough, means for winding said strand into a roll and securing the latter against the face of said shield, a flexible 70 exothermic pad adapted to extend over said roll, and means for securing the lateral edges of said pad between the flanges of said shield.

2. In combination in a hair waving apparatus, 75 a protective metallic shield having rigid upturned

flanges along opposite sides and a centrally disposed slot for passing a strand of hair there-through, a wrapper comprising a substantially rigid metallic base strip having two fabric sheets 5 connected thereto along adjacent edges, said wrapper being designed to wind said strand into a roll about said rigid base strip, a pair of relatively bendable wires extending from opposite ends of said strip for securing the roll against the face of said shield, a flexible exothermic pad 10 adapted to extend over said roll, and a second pair of relatively bendable wires connected to the ends of said strip for securing the lateral edges of said pad between the flanges of said 15 protective shield.

3. A protective shield for use in a hair waving apparatus, comprising a plate having rigid upturned flanges along opposite sides thereof, a centrally disposed restricted slot for retaining a 20 strand of hair in flattened position therein, and a laterally extending connecting slot through one side and flange thereof to permit the strand to be passed into said centrally disposed slot.

4. A protective shield for use in a hair-waving apparatus, comprising a metal plate having a heat-reflecting upper surface and rigid upturned flanges along opposite sides thereof, said plate 25 also having a centrally disposed restricted slot for retaining a strand of hair in flattened position therein, and a laterally extending connecting slot through one side and flange thereof to permit the 30

strand to be passed into said centrally disposed slot.

5. A wrapper for use in a hair waving apparatus, comprising two fabric sheets connected along adjacent edges to a substantially rigid base strip, 5 and a pair of bendable wires extending from each end of said strip to form a pair of independent holding devices at each end of said wrapper.

6. A wrapper for use in a hair waving apparatus, comprising a pair of bendable wires, two fabric sheets having adjacent edges engaging said wires, and a sheet metal base strip clamped over the central portion of said wires and the adjacent edges of said sheets to hold the several parts of the wrapper in permanent assembled position, 10 15 with the bendable ends of the wires extending from each end of said base strip to form a pair of independent holding devices at each end of said wrapper.

7. A wrapper for use in a hair waving apparatus, comprising two fabric sheets connected along adjacent edges to a substantially rigid base strip so as to receive the ends of a relatively flat strand of hair adjacent said base strip, and bendable wires extending from opposite ends of said base 20 25 strip so that said sheets and strand may be rolled about said strip and the completed roll may be held in place by bending said wires reversely along the outer sides of the roll.
